UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,162,076.

Specification of Letters Patent. Patented Nov. 30, 1915.

Application filed May 19, 1911. Serial No. 623,157.

To all whom it may concern:

Be it known that I, CHARLES J. KLEIN, a citizen of the United States, residing at Milwaukee, in the county of Milwaukee, and State of Wisconsin, have invented new and useful Improvements in Electric Switches, of which the following is a full, clear, concise, and exact description, reference being had to the accompanying drawing, forming a part of this specification.

10 My invention relates to electric switch devices.

One of the objects of my invention is to provide an improved electric switch of extremely simple, efficient, compact and inexpensive construction.

15 A further object of my invention is to provide an electric switch, comprising a plurality of independently operable switch mechanisms mounted in a single casing, adapted to make and break one or more circuits with a quick snap action and a minimum sparking.

20 A further object of my invention is to provide an improved switch casing which is adapted to house a plurality of switch mechanisms so that the parts of the latter are fully protected and at the same time readily accessible when desired.

25 Other objects and advantages of my invention will hereinafter appear.

30 In the accompanying drawings I have shown one form which my invention may assume in practice. This form has been chosen for purposes of illustration only and my invention itself is in no way limited to this specific form but may assume various other forms and be widely modified without departing from its spirit.

35 In the views of these drawings:—Figure 1 shows a partial central sectional view of the assembled switch. Fig. 2 shows a transverse sectional view on line 2—2 of Fig. 1. Fig. 3 shows an elevation of the interior of one of the halves of the switch casing. Figs. 4 and 5 show detail views of the switch contactor.

40 In these figures I have shown two switch mechanisms of the push button type arranged one above the other and inclosed in a two part casing carrying the terminal connections for two circuits. This casing is arranged to be clamped together by a transversely extending screw which passes through the casing at a point between the switch mechanisms. The top of the casing is in-

closed in a cap provided with suitable means for attaching it to the top of the casing and with a suitable conductor gasket through which the conductors may extend to the switch terminals.

45 In a preferred form the switch mechanisms are of the type described in my previously granted Patent No. 985,421, patented February 28, 1911. This mechanism includes a reciprocable cam 1 of the conformation of a double frustum, positioned base to base, having flanges 2 at its reduced ends and oppositely extending push buttons 3, of a smaller diameter than the flanges 2, 70 abutting against the outer vertical surfaces of the flanges and arranged to extend through openings in opposite sides of the casing.

50 A contactor 4 having central perforations 5 of a sufficient size to permit the passage of the cam 1 through the same is mounted upon the cam member and arranged to be reciprocated upon the movement of the same as the push buttons are pushed in and out. 75 In a preferred form the body portion of this contactor 4 is bent backward substantially at right angles at its opposite sides, as shown in Fig. 4, and then bent forward to form rearwardly extending rounded shoulders 6 having projections 6^a and forwardly extending side pieces 7 which extend substantially at right angles to the body portion of the contactor and beyond the front surface of the same. The forward edges of 90 these side pieces 7 are slightly peaked as at 8 and are turned slightly outward as indicated at 9. A spacing strip 10, perforated at 5, and having laterally extending shoulders 11 at its corners is carried in notches 95 12 in the top and bottom edges of the side pieces 7 so that the shoulders 11 fit snugly within the notches 12. In a preferred form holes 13 are provided in the body portion of the contactor 4 at points in the line along 100 which the side pieces are bent, to facilitate the bending of the side pieces and to give resiliency to the contactor. A garter spring 14 is carried between the spacing strip 10 and the body portion of the contactor. This 105

garter spring gives the snap action to the switch mechanism. In a preferred form slots 15 are formed in the sides of the side pieces 7 between the spacing strip 10 and the body portion of the contactor so that the spring 14 may expand freely without rubbing against the walls of the contactor, when 110

the crest of the cam is passed through the spring.

In a preferred form two such switch mechanisms are mounted one above the other in the same plane and parallel as shown in Fig. 1 between the two halves 16 and 17 of a substantially cylindrical casing having an open upper end and a closed lower end. This casing is preferably constructed of insulating material and the halves of the same are arranged to be fitted together, as shown in Fig. 1, and held in assembled relation by a transversely extending screw 18 carried in a recess 19 in a transversely extending septum 20 in the casing member 17, and received in a recess 21 in the casing 16, registering with the recess 19. If desired this screw may carry a suitable insulating washer 22 arranged to be housed in a suitable recess 23 in the inner surface of the casing 16 around the recess 21 when the parts are assembled. Suitable recesses 24 and 25 at the opposite ends of the recesses 19 and 21 respectively, permit the ends of the screw 18 to be housed within the periphery of the casing members and at the same time permit access to the same. In a preferred form the screw 18 is located in the same plane as the push buttons 3 of the switch mechanisms and lies parallel with these push buttons and between the same, as shown in Fig. 1. In order to house the contactors 4, chambers 26 of a substantially rectangular cross section are formed in the inner casing member 17 above and below the septum 20. As shown in Fig. 1 the left hand side walls of the chambers 26 provide stops for the contactors 4 in their backward movement. Communicating with the chambers 26 are transversely extending recesses 27 of a substantially circular cross section. These chambers are arranged to receive the flanged ends of the cam member 1 and when the cam is pushed to the left to the position occupied by the lower cam member, illustrated in Fig. 1, the side walls of the recesses 27 serve as stops for the cam members. Connecting with the recesses 27 are circular recesses 28 of reduced cross section, extending through to the outside of the casing members. These recesses 28 provide guides for the reciprocable outwardly extending push buttons 3. If desired the mouths of these recesses may be slightly enlarged around the ends of the push buttons as shown at 29 in Fig. 1. In a preferred form a wall 30 of the same height as the septum 20 extends entirely around the chambers 26. This wall is adapted to fit quite snugly in a substantially rectangular shaped recess 31 formed in the inner surface of the casing member 16 and in a preferred form the interfitting faces are slightly sloped as shown in Fig. 2. The interior of this casing member 16 is illustrated in Fig. 3. Centrally located in the casing member 16 are trans-

versely extending recesses 32 and 33 corresponding to and registering with the recesses 27 and 28 in the casing member 17 and having the same functions as these last mentioned recesses. As heretofore indicated the recess 21 lies between the push buttons 3 and therefore between the sides of two sets of recesses 32 and 33. At the sides of the recesses 32 and 33, longitudinal extending recesses 34, 35 and 36 are provided in the bottom of the recess 31. In the construction shown in Fig. 3 the recesses 35 and 36 are at the right of the recesses 32 and 33, while the recess 34 is at the left. As illustrated in this figure these recesses are arranged to receive the shanks of terminals 37, 38 and 39. The terminal 37 is provided with a long shank which extends substantially from one end of the casing member 16 to the other, and throughout the greater portion of its length is of a substantially rectangular cross section. At its upper end this terminal 37 is provided with a slightly offset enlarged head 40 carried in a recess 41 in the upper end of the casing member and fixed to the same by a transversely extending screw 42 extending through the casing member and accessible from the outside of the same. In a preferred form the upper end of the head 40 is bent slightly backward and the chamber 41 is so shaped as to carry the head flat upon its bottom. A binding screw 43 passes through the head 40 and has its threaded end housed in the recess 41 in the base member. In a preferred form the sides of the chamber 41 are slightly dished as at 44 to permit the ready manipulation of the contact screw, and ears 45 are provided on opposite sides of the head 40 beneath the contact screw 43 and a lug 46 bent substantially at right angles to the body of the head 40 is provided above the contact screw 43. These ears 45 and the lug 46 assist in permitting a good terminal connection to be made to the binding screw 43.

As illustrated in Fig. 3, the recess 35 and the shank of the terminal 38 housed within the same are shorter than the recess 34 and the shank of the terminal 38 just described. The upper end of the terminal 38 is similar to the upper end of the terminal 37 and is carried in a similar recess in the casing member and similarly secured to the casing. In a preferred form the upper portion of the recess 36 is not as deep as the recesses 34 and 35 and the terminal member rests flat upon its bottom. In a preferred form a septum 47 is provided about midway of the recess 34 to support the shank of the terminal 37 above the bottom of the recess. The lower end of the terminal 39 is bent laterally as shown at 48 in Fig. 3, and extends vertically downward from that point in the plane of the terminal 38. In a preferred form the shank of this terminal, below the

point 48, is supported above the bottom of the recess, just as in the case of the terminal 37. The lower ends of both the terminals 37 and 39 are bent slightly inward, as indicated at 49 in Fig. 1, and may be sealed in a correspondingly shaped recess 50. The terminal 39 is provided with a head similar to that of the terminals 37 and 38, similarly seated in the casing, while the recesses in 10 which the heads of the terminals 37 and 38 are seated may communicate through a recess 51 the recess in which the head of the terminal 39 is seated preferably does not communicate with the adjoining recess. If 15 desired the wall between the terminals 38 and 39 may be made slightly higher than the wall between the terminals 37 and 38. In a preferred form the upper end or head of the terminal 38 is bent slightly farther 20 backward than the heads of the terminals 37 and 39, and the recess in which it is seated is correspondingly sloped.

When the parts are assembled the switch mechanisms are located as shown in Fig. 1 25 and the two halves of the casing are held together by the transversely extending screw 18. The wall 30 around the chambers 26 fits securely in the recess 31 in the casing member 16 so that the switch mechanism is 30 entirely inclosed. The binding screws for the terminal members 37, 38 and 39 are accessible from the upper end of the casing. In a preferred form the upper inner surface 35 of the casing member 17 is slightly cut away as at 52 to permit a more free access to these binding screws. The upper ends of the casing members are provided with an outer peripheral groove 53 arranged to receive the lower end of a cap 54. This cap 54 is 40 preferably formed of sheet metal and carries within a perforation in the upper end of the same an insulating conductor gasket 55 provided with a central groove 56 through which the conductors pass to the binding 45 screws. In order to properly insulate the parts, an insulating lining 57 is provided. This lining has its upper edge received in a 50 groove 58 in the lower surface of the conductor gasket 55, and extends downwardly as shown in Fig. 1, passing between the lower edge of the cap 54 and the casing members. In a preferred form the cap 54 and the insulating lining 57 are secured to the casing by oppositely located inwardly 55 extending screws 59 which are received in recesses 60 in the grooved upper ends of the casing members. In order to prevent the relative rotation of the insulating lining 57 and the cap 54, threaded bushings 61 adapted to receive the screws 59 may be set in the lower edge of the insulating lining. In a preferred form the cap 54 and the insulating lining 57 are indented or ridged as at 62 to prevent longitudinal displacement. Thus 65 it is seen that when it is desired to connect

my improved switch to two circuits or to one circuit all that it is necessary to do is to connect the necessary conductors for the desired circuits to the proper binding screws of the terminal members. Ready access to these 70 binding screws may be obtained by loosening these screws 59 and removing the cap 54. If desired the conductors may be knotted above these terminals within the cap 54. By the provision of the gasket in the 75 cap the conductors are provided with a smooth surface which is adapted to prevent the wear of their insulation and are also suitably insulated so that no static charge may be transmitted to the switch cap in case 80 this cap should be of conducting material.

Assuming that the terminals 37 and 38 are arranged in one circuit and that terminals 37 and 39 are arranged in another all that is necessary to do in my improved 85 switch is to push the upper push button to the left from the position shown in Fig. 1 to throw the contactors 4 to the right to close the first circuit and push the bottom button to the left to close the other circuit. 90 The contact edge of the side pieces of the contactor will advance along the outer edge of the terminals and engage the same with a wiping action which tends to keep the contact parts bright and clean. Due to my improved snap switch mechanism this circuit will be made very quickly, as soon as the spring is passed over the crest of the cam. Further when the contactor reaches the forward limit of its travel, that is when the 95 front surface of the spacing strip 10 abuts against the adjacent surface of the terminals, the cam member will have reached the left end limit of its travel and flange 2 will abut against the side wall of the recess 27. Thus it is seen that there is no strain upon the parts and that the circuit is closed quickly with little or no sparking, while the contact members are kept in good condition. When it is desired to open the circuit all 100 that it is necessary to do is to push the controlling cam member to the right to throw the contactor to open circuit position. When the contactors are moved to open circuit position the peaked outturned edges of 105 the contactors are separated from the side of the terminals with the same wiping action, and the spark thus formed between the contacts is cut down. Further, due to the provision of the resilient contactors the 110 shock of impact between the parts is absorbed to a great degree by the contactor.

By my improved construction I have provided an improved switch device adapted to make or break one or more circuits, in which 115 the switch mechanism is compactly housed and conveniently arranged so that it is readily accessible when it is desired to change the circuit connections.

By the use of my improved switch the 120

necessity for providing two separate switch mechanisms mounted in separate casings, as has heretofore been necessary, is obviated and one or more may be controlled at will 5 from a single point by simply operating the proper push buttons in a single switch casing. Further, by my improved arrangement I am able to cut down the necessary 10 number of parts materially, and render the mechanism exceedingly compact. The casing in which the switch mechanism is enclosed carries the operating mechanism securely housed and yet at all times its operating mechanism is readily accessible and may 15 be readily connected or disconnected as desired. Further, due to the improved manner in which I have arranged the switch mechanism, it is obvious that one or any 20 number of circuits may be controlled by a single device, the different circuits being controlled by different sets of push buttons, or if desired one or more circuits may be controlled by a single set of push buttons. Further, it is plainly evident that various 25 other types of switch mechanisms may be assembled within the casings to perform the functions herein described, and that the particular functions of the devices may be widely changed, and their construction 30 widely modified without departing from the spirit of my invention.

While I have in this application described specifically one form which my invention may assume in practice, I have chosen this 35 form only as a means of illustrating the principle of my invention.

My invention itself may obviously assume various other forms than that herein described and be adapted to various other uses, 40 and I accordingly wish to include all these various forms within the scope of this application and to be in no way limited or restricted to the specific construction described for purposes of illustration.

45 What I claim as new and desire to secure by Letters Patent is:—

1. In a pendent switch, in combination, a molded insulating casing, a plurality of switch mechanisms carried therein one above 50 the other and insulated from each other by said casing, the operating members of said mechanisms projecting through a vertical wall of said casing, vertically extending stationary contacts carried within said casing, 55 one of said contacts serving as a common contact for a plurality of said switch mechanisms, and terminal connections for all of said contacts accessible from the upper end of said casing.

60 2. In a pendent switch, in combination, a longitudinally divided casing of molded insulation, a plurality of switch mechanisms carried therein and having double-ended

push-button operating members extending without the walls of said casing, stationary 65 contacts carried on an interior face of said casing and arranged to be engaged and bridged by said switch mechanisms, said contacts extending adjacent one end of said casing, and terminal connections for said 70 contacts at said end of said casing.

3. A pendent switch comprising, in combination, a multipart insulating casing, a plurality of switch mechanisms carried between the parts of said casing and in alignment with each other, a stationary contact common to all of said switch mechanisms and a separate stationary contact for each of said switch mechanisms, said separate contacts having aligned engageable portions 80 equi-distant from the corresponding engageable portions of said common stationary contact.

4. A pendent switch comprising, in combination, a multipart casing having a plurality 85 of substantially closed chambers therein, a switch mechanism mounted in each of said chambers, a single contact extending within all of said chambers and separate contacts extending within each of said chambers, all 90 of said contacts having terminals without said chambers and adjacent an end of said casing.

5. A pendent switch comprising, in combination, a multipart casing of molded insulation, the parts of said casing having spaced open recesses constituting closed chambers separated by an insulating wall when the parts of said casing are brought together, a switch mechanism mounted within each of said chambers and supported by said casing parts, each of said mechanisms having an operating member projecting through a part of said casing, and means 100 for securing the parts of said casing together. 105

6. A pendent switch comprising, in combination, a longitudinally divided casing, a plurality of independently operable switch mechanisms loosely supported within said 110 casing, a common contact for all of said switch mechanisms and separate contacts for each of the same fixed on one of the adjacent faces of said casing, the parts of said casing having complementally located recesses to receive parts of said switch mechanisms and to hold the latter in operative position, and means to secure the parts of said casing together. 115

In witness whereof, I have hereunto subscribed my name in the presence of two witnesses.

CHARLES J. KLEIN.
